Specification for Design.

Patented June 7, 1921.

Application filed March 1, 1920. Serial No. 362,566. Term of patent 3½ years.

To all whom it may concern:

Be it known that I, GERTRUDE M. MORRILL, a citizen of the United States, and a resident of the city and county of San Francisco, State of California, have invented a new, original, and ornamental Design for a Display-Fixture, of which the following is a specification, reference being had to the accompanying drawings, forming part thereof, in which—

Figure 1 is a front elevation of the fixture of my invention.

Fig. 2 is a side elevation of the fixture of my invention.

The characteristic feature of this design consists in the flat sheet cut in the shape of a head and having features delineated thereon, and the hair dress arranged on and overlying a portion of the sheet and extending forwardly therefrom.

I claim:

The ornamental design for a display fixture, as shown and described.
